ABSTRACT

Attachable and detachable weights are applied to a racket frame at a distance from the geometric axis that passes through the center of the racket handle, in such a manner as to adjust and increase the racket's moment of inertia about that axis for normal play, and to alter the weight and the head-to-handle balance of the racket for normal play. This unique placement of the weights increases the effectiveness of the weights.

1 Claim, 4 Drawing Figures

TENNIS RACKET WITH HEAD FRAME WEIGHTING MEANS

BACKGROUND OF INVENTION

This invention provides persons with a means to improve the performance of a tennis racket or such, enabling the person to match the racket's playing performance with personal preferences, these preferences being variable and dependent upon environmental conditions, player's physical condition and current playing style.

The official rules of the game of tennis set no restrictions on the size, shape, or weight of a racket. Standard practice before this invention was to fix the racket weight and head-to-handle balance at manufacture as a consequence of the frame construction and permanent insertion of a weighted plug into the handle. Although this plug adjusts the head-to-handle balance of the racket, it is on the axis of the handle and thus has only a small effect on the moment of inertia about that axis.

In the past, there have been no purposeful provisions for adjusting the torsional moment of inertia about the axis through the handle. However the experiments of the inventor have shown that a significant increase in playing accuracy can be attained by increasing this torsional moment of inertia and thereby reducing the inadvertent deflection of the racket when the ball is hit off-the-center of the racket. This invention allows the purposeful and convenient adjustment of this torsional moment of inertia.

This invention also allows convenient and independent adjustment of the weight and head-to-handle balance of the racket. Previously a device had been proposed which employed a single sliding weight in the racket handle. This device altered the balance conveniently, but did not allow adjustment of the mass of the racket. Its effect on the torsional moment of inertia was negligible. Another proposed device consisted of a laced-on practice weight on the central (handle) axis of the racket. It was not envisioned for use in normal play, and was neither convenient to change nor of an appropriate weight to be used in normal play. Its position was inappropriate for adjustment of the torsional moment of inertia.

Until now, selection of a racket that best fit the player's needs was essentially a process of trying different, fixed rackets until encountering a racket that "felt" best. The differences in weight in question are relatively small. There is only a 17 percent difference between the lightest and heaviest of the recommended adult rackets. Within these small weight differences, too light a racket makes it difficult to obtain a smooth follow-through and unnecessarily strains the racket and the arm muscles during impact with the ball. Too heavy a racket, while imparting more momentum to the ball, generally results in slow stroking and unnatural tiredness of the playing arm. Most ranking players prefer a handle-heavy racket, but preferences vary, and have been one basis of selection of the preferred playing response of a racket. Some players had considerable funds or sponsors which would provide a wide range of rackets to try and select through a process of trial and error. The selection by other players was restricted to the few rackets they could try before buying or buy before trying. This narrowed their ability to attain their most preferable racket mass and balance.

SUMMARY OF INVENTION

A player of tennis or another racket sport plays with a racket which has provision to add weights to its frame, at a position distant from the central axis which passes through the center of the racket handle. The player thus, by adding weights or removing weights, changes the playing response of the racket to fit his current preference, through a process of convenient trial and error. Reacting to environmental or physical conditions or desire to pursue a different playing style, the player changes the mass, the head-to-handle balance and the torsional moment of inertia. (The tendency to resist twisting about the axis of the handle.) All these changes are possible because the weights are small enough to be used during normal play, and because the number of weights, the size of the weights, the composition of the weights, the distance of the weights from the end of the handle, and the distance of the weights from the axis of the handle can be changed. The player can, if desired correct a tendency to hit the ball off center to one side by distributing the weights unevenly on purpose. The weights are firmly attached, but easily removed or changed.

DRAWINGS

Preferred embodiments of the invention are illustrated in the accompanying drawings, wherein:

FIG. 1 shows in perspective, a bracket which holds detachable weights, and which can be attached to various points on an ordinary tennis racket by flexible straps.

FIG. 2 shows in perspective, weights which fit into and onto the bracket shown in FIG. 1, and which fit into and onto the provisions in the racket section shown in FIG. 5.

FIG. 3 shows in side elevation, a bracket attached to a tennis racket.

FIG. 4 shows in perspective, a racket with two brackets and a plurality of weights attached to it.

PREFERRED EMBODIMENT

The preferred embodiment shown in FIGS. 1, 2, 3 and 4 concerns a method to add the invention to an existing racket.

Bracket And Removable Weights

The slot 20 in the bracket 21 is closed at one end to provide the principal opposition to motion of the weights 22 in the slot 20 as the player swings the racket. Other mechanisms acting to keep the weights 22 in the slot 20 are the stiffness of the edges of the slot 20 reacting against the wide retaining base 23 of the weight 22, and the friction between the weight 22 and the bracket 21. If wear from usage results in excessive looseness of fit, the last weight 24 inserted in the slot 20 is composed of an elastomeric material and retains the other weights 22.

Bracket Mounting

The brackets 21 are held to the racket 25 by flexible straps 28 at positions distant from the central longitudinal axis 34. The bracket 21 deforms enough to fit the curvature of the racket 25 frame. This deformation is allowed by rounded grooves 27 in the base of the bracket 21, and by the plastic material of the bracket 21, and by the angular grooves 37 in the base of the

bracket 21. The angular grooves 37 also provide clearance for racket strings which protrude in some constructions, and the angular grooves 37 provide constraint to prevent slippage of the bracket 21 on the racket 25. Slippage of the bracket 21 is further prevented by the mounting straps 26 passing between, and contacting the strings 29 of the racket 25. Straps 26 are retained to the bracket 21 by tension in mounting and by nesting of straps 26 in groove means 30 and 30A at the ends of the bracket 21. Groove means 30A is configured as a deep rectangle to retain one or more straps 26. Groove means 30 is angular in shape to retain straps 26, and also simplify design of a mold for manufacture of brackets 21.

I claim:

1. In combination, a game racket and weighting means therefor, comprising: said racket having a closed loop head portion and a handle portion extending therefrom, said racket having a central longitudinal axis with said head portion symmetrically disposed thereabout, said weighting means being disposed on said head portion at transverse and symmetrical loca-

tions relative to said axis, each of said weighting means includes a bracket, a plurality of weights, and a plurality of flexible securement straps, each of said brackets having an outer surface and an inner surface, said outer surface having an upstanding portion, a dead-ended T-shaped slot formed in said upstanding portion, said slot further having overhanging flanges, said upper surface further including strap receiving groove means located on both ends of said upper surface, at least one of said groove means being disposed at a lower elevation than said slot, said inner surface being configured to conform to the outer curved surface of said head portion, said weights having at least a T-shaped formation and being slidably and removably disposed and frictionally held in said slot for increasing and decreasing the moment of inertia about said axis, said upstanding portion and flanges being of sufficient stiffness to further retain said weights in said slot, said straps being seated in said strap receiving groove means and being secured about said head portion thereby holding said brackets thereto.
